DESIGN FOR A GRATER

Irving Rosenbloom, New York, N. Y.

Application November 30, 1944, Serial No. 116,636

Term of patent 7 years

(Cl. D89—1)

To all whom it may concern:

Be it known that I, Irving Rosenbloom, a citizen of the United States of America, residing in New York city, county of New York, and State of New York, have invented a new, original, and ornamental Design for a Grater, of which the following is a specification, reference being had to the accompanying drawing, forming part thereof.

Fig. 1 is a front perspective view of a grater showing my new design.

Fig. 2 is a rear perspective view thereof.

I claim:

The ornamental design for a grater, substantially as shown.

IRVING ROSENBLOOM.
